UNITED STATES PATENT OFFICE.

EDWARD T. ROBINSON, OF ST. LOUIS, MISSOURI.

WINDOW CONSTRUCTION.

SPECIFICATION forming part of Letters Patent No. 784,707, dated March 14, 1905.

Application filed February 9, 1903. Serial No. 142,457.

To all whom it may concern:

Be it known that I, EDWARD T. ROBINSON, a citizen of the United States, and a resident of the city of St. Louis and State of Missouri, have invented certain new and useful Improvements in Window Constructions, of which the following is a specification.

My invention relates to window constructions, particularly to street-car windows, and has for its object the provision of means whereby the upper and lower sashes may be moved up and down and also may be removed from the window-frame independently of each other, also to attain certain other advantages hereinafter disclosed.

My invention consists in the construction and arrangement of parts hereinafter described and claimed.

In the accompanying drawings, wherein like symbols refer to like parts wherever they occur, Figure 1 is a front view of a car-window equipped with my invention. Fig. 2 is a cross-section thereof on the line 2 2 of Fig. 1. Fig. 3 is a cross-section of the post and portions of the window-sashes on opposite sides thereof, taken on the line 3 3 of Fig. 1. Fig. 4 is a vertical section on line 4 4 of Fig. 3, showing the pintle on the side of the upper sash in its proper position when the sashes are closed. Fig. 5 is a view in elevation of the window-sash, showing the bevel on the sash-stile. Fig. 6 is a cross-section of the post on line 6 6 of Fig. 2.

In the present construction the window-opening is formed by an upper framework 7, a lower framework 8, and vertical posts 9. In the lower framework 8 is formed a sash-receiving pocket 8^a, which receives both the upper and lower sashes when lowered thereinto. The posts are provided with means for holding the upper and lower sashes in their closed position, as indicated in Fig. 2, and with means for permitting the sashes to be lowered and raised and to be removed from the window-frame. The post 9 is made from a single piece of material and is of a construction more particularly shown in Fig. 6. On the inner side of the post a molding 10 is secured, which overlaps a reduced portion 11 of the post to which it is secured. Adjacent to this reduced portion 11 there is formed a

tongue 12, which with the overlapping portion 10 on the molding forms a groove 13, which is intended to be used to receive the edges of a curtain or blind. Adjacent to the tongue 12 there is formed a sash-groove 14, which receives a suitable projection, as a pintle or pin 15, on the upper-sash frame. Said pintle or pin is preferably a small casting secured to the frame by a screw; but it is obvious that this projection may be secured in a number of ways. This groove 14 runs parallel with the curtain-groove 13 and extends from the sash-receiving pocket to the upper portion of the post. At the upper portion of the post this groove is curved rearwardly and downwardly, terminating in a seat 16, in which a pintle 15 rests when the upper sash is in its normal or closed position. About the point where the sash-groove 14 begins to make its rearward bend a passage-way 17 is formed, which communicates with said groove 14. This passage-way or slot is formed in but one of the posts—that is, only in one of the posts which form a single window-opening.

Adjacent to the upper-sash groove 14 there is formed on the post a tongue 18, constituting a parting-strip, which terminates considerably short of the upper end of the post, as shown clearly in Figs. 1 and 2. This tongue 18 is preferably integral with the post; but it may be a separate piece. Between this tongue and the outer portion of the post there is formed a groove 19, which receives the lower sash. The outward movement of the lower sash is limited by an inclined shoulder 20, forming the outer wall of the groove, and the outward movement of the upper sash is limited by the usual shoulder 21 and grooved rest 22. The upper portion of the parting-strip 18 is beveled toward the upper end, as shown in Fig. 1, the length of the bevel being proportioned to the length of the lower sash, so as to permit the removal of the same, as hereinafter described. The point of beginning said bevel is indicated on Fig. 2 of the drawings by 18^a. Also the lower portion of the lower sash is beveled, as shown at 18^b, Fig. 5. The purpose of beveling these parts is to permit the removal of the lower sash, as will be hereinafter described. To the stile

on the lower sash is secured a spring 31, which bears against the parting-strip 18, which is for the purpose of holding the sash firmly in place and preventing rattling of the same 5 and for forming a friction-brake to prevent too quick a downward movement of the sash when it is lowered into the sash-receiving pocket.

Hinged to the inner side of the upper lining of the sash-receiving pocket 8^a is a cover 23, the outer edge of which is rabbeted, as shown at 24. The outer lining 25 of said sash-receiving pocket is beveled, as indicated at 26. The outer edge of the cover 23 projects beyond the inner edge of the lining 25 and over the beveled portion 26. On the lower rail of the lower sash there is formed a shoulder which snugly fits the rabbeted portion of the cover 23. By this construction 15 a close-fitting cover is formed for the sash-receiving pocket, thereby presenting a neat appearance and also serving to prevent passengers from throwing into the sash-receiving pocket refuse—such as banana-peelings, 20 peanut-shells, and the like.

On the lower sash-rail there is provided a sash-lift 27, composed, preferably, of leather. On the lower sash-rail of the upper sash there is secured in any suitable manner a sash-lift 30, 28, which is also preferably formed of leather. Immediately below this sash-lift there is secured on the upper rail of the lower sash another sash-lift, 29, which is preferably formed of metal, as brass or the like, and which is 35 provided with an outwardly-extending portion 30, which projects beyond the outer edge of the sash-rail in such a position that when the lower sash is lifted it comes into contact with the sash-lift 28, by which its 40 further upward movement is restricted. In order to prevent rattling and keep the top sash firmly seated in its rests, a strong spring 33 is arranged at the top of the window-opening in position to bear against the upper rail 45 of the top sash.

In the normal or closed position of the parts the sashes rest in the positions shown in Figs. 1 and 2. If it is desired to lower both sashes into the sash-receiving pocket, the 50 sash-lift 27 is grasped and the sash is lifted thereby until the rear part of the projection 30 comes in contact with the sash-lift 28. When the sash has reached this position, a knob 32 on the cover 23 is grasped in the 55 hand and the cover is turned inwardly on its hinge. It is obvious that when the lower sash is lifted to a slight extent the rabbeted edge of the cover will be able to clear the lower sash-rail and the sash-lift 27 secured thereto. When the cover 23 has been turned 60 inwardly, the lower sash is drawn forward and dropped into the receiving-pocket. The sash-lift 28 is then grasped, by which means the upper sash may be lifted, (the pin 15 being unseated,) and the sash may then be 65

drawn forward and also lowered into the sash-receiving pocket. It is obvious that the upper sash can be lowered without disturbing in any way the position of the lower sash, since the height of the groove 14 is sufficient to permit the lower sash-rail to clear the upper rail of the lower sash. 70

For the purpose of permitting the pin 15 to be drawn inward beyond the post 9 after it has passed through the passage-way 17 the 75 post is reduced in width at the inner side, as indicated clearly at 34 in Fig. 6, so that when the molding 10 is secured to the inner face of the post with the edges overlapping equally the edges of said face to form the curtain-groove 13 the edge of the molding on one side is still inside of a line passing through the bottom of the sash-groove 14, whereby the inward movement of the sash is unobstructed 80 when the pin 15 is drawn out of its groove. 85

When it is desired to remove the lower sash, the sash-lift 27 is grasped and the sash is raised until the beveled portion 18^b of the side stile thereof comes into a position opposite to the beveled portion on the parting-strip 18, when the sash may be freely drawn forward. In order to permit this upward movement, the upper sash will first have to be slightly lifted. 90

It is obvious that it will not be necessary 95 to bevel both the sash-stile and the parting-strip, but that the sash could be made removable by beveling only one of these parts.

Obviously the construction hereinbefore described admits of considerable modification without departing from my invention, 100 and I do not wish to be restricted to the specific construction hereinbefore described.

What I claim is—

1. A window construction comprising a 105 window-frame, a movable window-sash, a sash-groove in the window-frame having a rearwardly and downwardly curved portion terminating in a seat, means on the window-sash engaging said groove and resting in said 110 seat when the sash is in its normal position, and a passage-way leading from said groove but stopping short of the forward edge of the frame, whereby the sash may be freely removed without disturbing the connecting 115 parts.

2. A window construction comprising a 120 window-frame having two vertical posts, upper-sash grooves in said posts, a passage-way leading from one of said grooves but stopping short of the inward edge of said post, a sash sliding between said posts, and projections on said sash engaging the said sash-grooves, and traveling in the said passage-way when the sash is being removed from the 125 frame.

3. A window construction comprising a window-frame having two vertical posts on opposite sides, upper-sash grooves in said posts, a sash sliding between said posts, pro- 130

jections on said sash engaging the said grooves, and a passage-way leading from the groove in but one of the posts, whereby the sash may be removed from the frame without changing the position of any part of the frame.

4. A window construction comprising a window-frame having two vertical posts on opposite sides, a sash sliding between said posts, an upper-sash groove in each of said posts, projections on said sash engaging said grooves, a curtain-groove in each of said posts, and a passage-way leading from the said upper-sash groove to the said curtain-groove whereby the said sash may be removed from the frame without changing the position of any part of the frame.

5. A window construction comprising a window-frame having two vertical posts, upper-sash grooves in said posts, curtain-grooves in said posts, the bottoms of the grooves in one post being in the same plane and the bottoms of the grooves in the other post being in different planes, a passage-way leading from the sash-groove to the curtain-groove of the latter post, a sash sliding between said posts, and projections on said sash engaging the said sash-grooves.

6. A window construction comprising a window-frame having two vertical posts on opposite sides, sash-grooves and curtain-grooves in said posts, the front wall of the curtain-groove in one post extending laterally not farther than the vertical plane of the bottom of the sash-groove in the same post, a passage-way leading from the said sash-groove to the said curtain-groove, a sash sliding between said posts, and projections on said sash engaging the said sash-grooves.

7. A window construction comprising two members, viz.—a window-frame and a movable window-sash, and a parting-strip on the window-frame, one of said members being beveled whereby when the sash is moved into an abnormal position it may be removed without disturbing the parting-strip.

8. A window construction comprising a window-frame, a movable window-sash, a parting-strip on the window-frame, the upper part of the said parting-strip and the lower part of the sash-stile being beveled whereby when the sash is raised it may be freely removed without disturbing the parting-strip.

9. A window construction comprising a window-frame having two vertical posts, parting-strips on said posts terminating short of one end of the frame, and shoulders on the outer edge of said posts, said parting-strips and said shoulders bounding a groove to receive a sash, no part of the posts forward of the parting-strips projecting laterally beyond the plane of the bottom of the said sash-groove, whereby a sash may be removed from the frame without changing the position of any part of the said frame.

10. A window construction comprising a window-frame having two vertical posts, integral parting-strips on said posts terminating short of one end of the frame, integral shoulders on the outer edge of said posts, said parting-strips and said shoulders bounding a groove to receive a sash, upper-sash grooves and curtain-grooves in said posts inward of said parting-strips, the walls of said grooves projecting laterally not farther than the bottoms of the said sash-grooves formed by said parting-strips and shoulders.

11. A window construction comprising a window-frame including vertical posts on opposite sides, upper-sash grooves in the sides of said posts, a sash, and projections on the sash taking into said grooves, and a passage-way leading from the groove in one post, the inward portion of said post being reduced in width, whereby the sash may be freely removed from its seat.

St. Louis, Missouri, February 7, 1903.
